BY

Geo. P. Kimmel.

ATTORNEY.

UNITED STATES PATENT OFFICE.

CHARLES P. GRAY, OF WEST CHESTER, PENNSYLVANIA.

DEVICE FOR MAKING SPIRAL WIRE FASTENERS.

Application filed April 11, 1922. Serial No. 551,482.

To all whom it may concern:

Be it known that I, CHARLES P. GRAY, a citizen of the United States, residing at West Chester, in the county of Chester and 5 State of Pennsylvania, have invented certain new and useful Improvements in Devices for Making Spiral Wire Fasteners, of which the following is a specification.

This invention appertains to certain improvements in devices for making spiral wire coils generally, and more particularly to a type of the same adapted for making spiral wire fastenings for use as pivots for the securing together of the moving parts of 15 mechanical postcards and the like.

The principal object of the invention is to provide for a device of the class mentioned, and one of an extremely simple, inexpensive and efficient construction and arrangement of parts wherein the exceedingly fine and delicate wire fasteners, required for use in connection with the manufacture of mechanical postcards, will be accurately formed directly at and in their places of use.

Another object of the invention is to provide for a novel method of forming fastenings or pivots for the moving parts of mechanical postcards or the like, which consists in passing a suitable length of fine wire 30 through the parts to be fastened or pivoted together, and then coiling the oppositely projected ends of the wire into tightly wound spiral coils, flat against the oppositely disposed or outer faces of the parts to be fastened or pivoted together.

With the foregoing and other objects in view, the invention resides in the certain new and useful construction, arrangement and operation of parts as will be hereinafter 40 more fully described, set forth in the appended claims, and illustrated in the accompanying drawing, in which:—

Figure 1 is a side elevation of a preferred embodiment of wire coiling device,

Fig. 2 is a sectional view of the device,

Fig. 3 is an enlarged sectional detail of the coil forming end of the device, and showing the manner of operation of the same,

Fig. 4 is an enlarged fragmentary elevation of the coil forming end of the device,

Fig. 5 is a face view of the lower coil forming end of the device with the work holding member removed therefrom,

Fig. 6 is an enlarged fragmentary plan view of the guard for facilitating the accu-

rate centering of the device over the work, and

Fig. 7 is a fragmentary plan view of a portion of an article, such as a mechanical postcard or the like, and showing one of the completed fasteners as applied thereto.

Referring to the drawing, wherein similar characters of reference designate corresponding parts throughout the several views thereof, the reference character *a* indicates a table or work support; *b* and *c* the lower and upper superimposed portions of a mechanical postcard or the like; and *d* the length of wire fastening which is passed through the parts of the postcard in a manner to 70 provide end portions of substantially equal length at the opposite sides thereof for the forming of the same into flat spiral coils, as at *e* in Fig. 7.

The device or machine for forming the 75 spiral coils *e* comprises a metal frame formed of an upper inclined bracket bar 10 having its upper free end formed to provide an apertured attaching ear 11 for the reception of a screw or the like 12, by means of which is 80 secured to an upright, carried by the work table or support, or otherwise arranged adjacent thereto. Dependently supported from the bracket bar 10, by means of a vertical bar 13, is a lower frame bar 14, which is preferably inclined in a direction reverse to the inclination of the bar 10, and formed at the forward free convergent ends of both of these bars 10 and 14, are alined bearing portions 15 and 16, respectively. 90

Journalized in the bearing portions 15 and 16, is a hollow or tubular spindle 17, on which, between these portions 15 and 16, is secured, by means of a set screw 18, a pulley 19 which is tensioned with its upper hub face 95 bearing against the under side of the upper bearing portion 15 by means of a coiled spring 20 carried on the spindle 17 and interposed between a washer 21, seated in a depression 22 formed in the lower face of the pulley 19, and the upper face of the bearing portion 16 for the purpose. The lower end portion of the hollow spindle 17 is stepped as at 17' to provide an extreme lower end portion 17'' of an appreciable less diameter 105 than that of the upper portion thereof, which portion 17'' has its end edge formed to provide a series of teeth, each formed with slightly undercut leading wall portions 23 and curved trailing wall portions 23', and 110

one equidistantly spaced from the other to provide flat end faces 23" therebetween.

Extending downwardly of the bore of the spindle 17 is a plunger 24, which has an 5 enlargement 25 formed at its upper end. This enlargement 25 is longitudinally slotted as at 26 for sliding engagement over the inner end of a set screw 27 carried by a cap 28 engaged over the end of the plunger 24 10 and the upper end of the sleeve 29, which is mounted on the plunger 24 below the enlargement 25. The upper end of the sleeve 29 is counter-bored to allow for sliding movement therein of the enlargement 25 of 15 the plunger 24, and bearing against the upper end of the enlargement 25 is a coiled spring 30 housed within the bore of the cap 28. Interposed between the upper end of 20 the tubular spindle 17, and the opposed lower end of the sleeve 29, is a washer 31 arranged on the plunger 24 to compensate for wear between these parts of the device, and for the slight shortening of the spindle 17 occasioned by the sharpening of the teeth 25 23 at the lower end thereof. The lower end of the plunger 24 is formed to provide a small projection 32, the purpose of which will be hereinafter more fully explained.

Adapted to be used with the device as 30 hereinbefore described, and between the working end of the same and the work to be acted on thereby, is a guard consisting of a very thin metal plate 33, on the longitudinal center of which is provided a circular 35 opening 34, and leading outwardly from the opening, on a curved line, is a slotway 35 which is of a much less width than the diameter of the circular opening 34.

In the use of the device, the same is 40 secured in position over the work table or support *a* with the working end of the spindle 17 spaced about a quarter of an inch above the surface thereof, when the superimposed portions *b* and *c* of a mechanical 45 postcard or the like will be positioned under the spindle 17, substantially as shown, with the guard plate 33 interposed therebetween. The postcard parts *b* and *c* are first placed one on the other in a desired manner, and 50 a fastening wire *d* is then passed through the same with its opposite ends, preferably of equal length, bent down against the upper and lower flat surfaces of the parts.

The guard 33 is now placed in position with 55 the circular opening 34 thereon disposed over the part of exit of the upper end of the wire *d* from the card parts *b* and *c*, and is centered directly under the reduced end 32 of the plunger 24, and the bent end of the 60 wire *d* is passed outwardly of the slotted side of the opening 34. With the parts thus positioned, the plunger 24 is now depressed by one hand of the operator, so that the projection 32 enters the opening 34 to one 65 side of the vertical portion of the wire *d*

therein, and the shouldered end portion of the plunger 24 abuts the upper face of the guard 33, when the latter will be withdrawn from beneath the device, the wire *d* and the projection 32 passing outwardly of the slot 70 35. With power now applied to the pulley 19, through the medium of an endless belt 36, the spindle 17 will be rotated in a direction to have the upper bent end of the wire *d* engage in one of the teeth 23 of the 75 lower end of the spindle 17, when the same will be coiled about the projection 32 substantially as is shown in Fig. 7. The length of the projection 32 is only sufficient to engage in the opening 34 of the guard or 80 centering plate 33, so that it will not penetrate the paper or cardboard parts *b* and *c* beneath the latter, when the plunger 24 is brought downwardly at the start of the operation. The coil spring 30, in the cap 28 85 at the upper end of the plunger 24, acts to prevent the successive coils of the fastening *e* from overlapping one another during the winding or coiling operation, while, at the completion of the coiling operation and 90 upon relieving the pressure of the hand on the capped end of the plunger 24, the coil spring 20, below the pulley 19, acts to lift the spindle 17 from the work.

After the operation of the device for the 95 forming of a coil *e* at one side of the postcard, the latter is reversed to bring its under side in position to have the other end of the wire *d* similarly formed to provide a coil *e*, and the normal formation of both coils admits of the fasteners being used as pivots for moving parts of mechanical postcards and the like, but, by pressing the coils slightly toward one another, the same may be used after the manner of ordinary fastenings for securing two or more immovable parts together.

From the foregoing, it will be readily apparent that, while a preferred embodiment of the device has been described and illustrated herein in specific terms and details of construction, arrangement and operation, various changes in and modifications of the same may be resorted to without departing from the spirit of the invention, or the 110 scope of the claims appended hereto.

Having thus fully described, the invention, what is claimed, is:

1. The method of fastening together the parts of mechanical postcards or the like, 115 which consists in superposing the parts one on the other, passing through the parts a length of wire, and then coiling the opposite ends of the wire into flat spiral coils in abutting relation to the outer opposite sides of 120 the parts.

2. The method of pivoting the movable parts of a mechanical postcard or the like one to the other or otherwise in operative 125 position, which consists in superposing the 130

parts one on the other, passing through the parts a length of wire, and then coiling the opposite ends of the wire into flat spiral coils disposed in abutting relation to the outer opposite sides of the parts.

3. The method of fastening together of the parts of mechanical postcards or the like, which consists in superposing the parts one on the other, passing through the parts

10 a suitable length of wire in a manner to leave end portions of equal length projecting from the outer opposite sides of the parts, bending the end portions downwardly against the outer opposite sides of the parts,

15 coiling the end portions of the wire into flat spiral coils, and then subjecting the spiral coils to slight pressure, whereby to dispose the same in closely abutting relation to the outer opposite sides of the parts.

20 4. In a device for forming spiral wire fasteners, a frame, bearings supported in vertical alinement on said frame, a rotating hollow spindle journaled in said bearings and having a plurality of teeth formed at its lower end, a plunger slidably mounted in said spindle, and a projection formed on the end of said

25 plunger and disposed outwardly of the toothed end of said spindle for the coiling around the same of a length of wire engaged in one of the teeth of the spindle.

5. In a device for forming spiral wire fasteners, a frame, bearings supported in vertical alinement on said frame, a rotating hollow spindle journaled in said bearings and having a plurality of teeth formed at its lower end, a plunger slidably mounted in 30 said spindle, and a projection formed on the end of said plunger and disposed outwardly of the toothed end of said spindle for the coiling around the same of a length of wire engaged in one of the teeth of the spindle.

35 6. In a device for forming spiral wire fasteners, a frame, bearings supported in vertical alinement on said frame, a rotating hollow spindle journaled in said bearings and having a plurality of teeth formed at its lower end, a plunger slidably mounted in said spindle, and a projection formed on the end of said plunger and disposed outwardly of the toothed end of said spindle for the coiling around the same of a length of wire engaged in one of the teeth of the spindle.

40

parts one on the other, passing through the parts a length of wire, and then coiling the opposite ends of the wire into flat spiral coils disposed in abutting relation to the outer opposite sides of the parts.

5. The method of fastening together of the parts of mechanical postcards or the like, which consists in superposing the parts one on the other, passing through the parts

10 a suitable length of wire in a manner to leave end portions of equal length projecting from the outer opposite sides of the parts, bending the end portions downwardly against the outer opposite sides of the parts,

15 coiling the end portions of the wire into flat spiral coils, and then subjecting the spiral coils to slight pressure, whereby to dispose the same in closely abutting relation to the outer opposite sides of the parts.

20 4. In a device for forming spiral wire fasteners, a frame, bearings supported in vertical alinement on said frame, a rotating hollow spindle journaled in said bearings and having a plurality of teeth formed at its lower end, a plunger slidably mounted in said spindle, and a projection formed on the end of said plunger and disposed outwardly of the toothed end of said spindle for the coiling around the same of a length of wire engaged in one of the teeth of the spindle, said resilient means 45

acting to move the spindle to normally inoperative position when said plunger is released.

7. In a device for forming spiral wire fasteners, a frame, bearings supported in vertical alinement on said frame, a rotating hollow spindle journaled in said bearings and having a plurality of teeth formed at its lower end, a plunger slidably mounted in said spindle, and a projection formed on the end of said plunger and disposed outwardly of the toothed end of said spindle for the coiling around the same of a length of wire engaged in one of the teeth of the spindle, said resilient means 50
